UNITED STATES PATENT OFFICE.

JOHN SHANNON AND JAMES E. WOOD, OF PORTLAND, OREGON.

RAILWAY BLOCK-SIGNAL.

No. 900,315.

Specification of Letters Patent.

Patented Oct. 6, 1908.

Application filed May 9, 1908. Serial No. 431,933.

To all whom it may concern:

Be it known that we, JOHN SHANNON and JAMES E. WOOD, citizens of the United States, residing at Portland, in the county of Multnomah, State of Oregon, have invented a new and useful Railway Block-Signal, of which the following is a specification.

This invention has reference to improvements in railway block signals, and its object is to provide a means whereby, when a semaphore or target on the line of way, is set at danger an operating member in the track will be moved into the path of another operating member upon a locomotive engine so that the two members coöperating will cause the air brakes to be set when the engineman fails to stop on the display of the danger signal.

This invention is an improvement upon the railway block signal shown in Letters-Patent #863,102, granted to us on August 13, 1907. The invention set forth in the aforesaid Letters-Patent consists essentially of an inclined member in the track or along the line of way, connected to and operated by the target-setting mechanism. There is provided an air pipe coming from the air brake system, which air pipe carries an air valve so located beneath the engine as to be in the path of a reciprocating member also carried by the engine and actuated by the inclined member in the line of way, when the said inclined member is sufficiently elevated to come into the path of the engine-carried member. In accordance with the said invention set forth in the said Letters-Patent, the air valve may also have a connection to a point within reach of the engineman so that the air may be closed off when it is desired to release the brakes in the usual manner.

The present invention comprises improvements in the track member, whereby the latter is better adapted for the purposes of the invention, and also improvements in the member carried by the engine, so that the engine-carried member coacts with the track member in a better manner than is the case with the structure shown in the Letters-Patent.

The invention also comprises improvements in other features of the structure, all of which will be best understood from a consideration of the following detail description taken in connection with the accompanying drawings forming a part of this specification, in which drawings,

Figure 1 is a diagram in perspective showing the application of the invention to the railroad of the single track type. Fig. 2 is a side elevation of the engine-carried member and a longitudinal section of the track member, the two members being in coöperative relation. Fig. 3 is an end elevation of the structure of Fig. 2 as viewed from the pilot end of the engine, parts being shown in section and broken away. Fig. 4 is a section of the track member on the line A—B of Fig. 2, and on a somewhat larger scale. Fig. 5 is a section on the line C—D of Fig. 2 but on a larger scale. Figs. 6, 7, 8, 9, 10 and 11 are detail views.

Referring to the drawings, and more particularly to Figs. 2, 3 and 4, the track member will be first considered. In referring to this member as the track member, it will be understood that the member is to be located either between the rails of a track or along the side of the rails at any point desired along the line of way, and there will be as many track members as there are signals to be operated. The system is a block system and consequently each track member will control a suitable semaphore or target or other signal at the block station.

In the figures referred to there is shown a base member 1 in the form of a plate of suitable width and length so that its ends may rest upon two ties 2, and from these ties the base member slopes downwardly toward the center from each end, as best shown in Fig. 2. The ends of the basic member 1 are bent upward and then are returned on themselves parallel with the base member but spaced therefrom, and finally terminate in a down-turned end approaching but still spaced from the basic member. The ends 3 thus form guides or pockets with narrowed throats opening toward the center of the basic member.

Rising from the basic member 1 are side members or wings 5 secured to the basic member near the sides thereof. These side members gradually increase in height from the ends of the basic member toward the center thereof where the side members are the highest.

The basic member 1 and the sides 5, which latter are parallel one to the other and spaced apart, constitute the stationary portion of the track member and between the ties 2 other supporting blocks or ties 6 may be provided.

The movable member of this device consists of two parts 7, 7, which are substantially U-shape in cross section, and having their side walls gradually decreasing in height from one end toward the other. The parts 7, 7 are joined at their angles by a pivot bolt or rod 8, and these two parts so pivoted together constitute a cover for the basic member, and the sides of these two parts 7, 7 straddle the sides 5 of the said basic member. The narrow ends of the parts 7, 7 are turned on themselves to form beads 9, which beads are housed in the pockets or guides 3, and the pockets are of sufficient length to permit a limited longitudinal movement of the beaded ends 9 with reference to the basic member 1.

On each side of the center of the basic member 1 there are fastened to the latter blocks 10, and similarly located on the top members 7 are other blocks 11. These blocks 10 and 11 receive the ends of strong expansion helical springs 12, tending at all times to lift the members 7 at their central points 25 away from the basic member 1. This movement, however, is limited by the engagement of the beads 9 with the downturned ends 4 of the guides 3.

Pivoted secured to the center of the rod 8 by means of an eye 13, is a link 14 the other end of which is formed into an elongated eye 15.

Through the central portion of the basic member 1 is an opening 16, and to one side 35 of this opening on the bottom of the basic member are two brackets 17 spaced apart and receiving between them a bell-crank lever 18, this lever being pivoted to the bracket 17 at one angle, by means of a pivot 40 bolt 19. The bell-crank lever is made up of two substantially triangular plates 20 spaced apart so as to receive at one end the elongated eye 15 of the link 14 by means of a rivet or bolt 21, and at the other end or angle 45 give one end of a link 22 by means of a rivet or bolt 23. The purpose of the link 22 will appear hereinafter.

In Figs. 2 and 3 a portion of an engine frame is indicated at 24. Fast on the frame 50 24 is a laterally-extending bracket 25 terminating in a pintle 26. Surrounding the pintle 26 is an eye clip 27 held in place thereon by a cotter pin 28, or in any other suitable manner. The clip 27 is fast to one end of a 55 shoe 29, preferably made of channel iron for lightness and strength. The shoe 29 normally extends downward at an angle, and its free end is upturned for a distance, as indicated at 30. The lowermost portion of the 60 shoe 29 is rounded in a longitudinal direction and is designed to engage the inclined upper surfaces of the members 7 of the track device. The free end 30 of the shoe 29 is supported by a chain 31 from the frame 24 and limits 65 the downward movement of the shoe 29 but

permits the shoe to be lifted to any desired extent.

Mounted on the engine frame is an air pipe 32 supported near its ends in brackets 33, in which the pipe 32 is capable of turning on a longitudinal axis. Beyond one of the brackets 33 the pipe 32 is screwed into the smaller end of a coupling 34, the other end of which is threaded to receive a bushing 35 having a plain central opening for the passage of a pipe 36 coming from the train pipe of the air brake system of the train. The pipe 36 enters the coupling 34 and is there formed with an annular flange 37 entering the counterbored portion of the bore of the coupling 34. The pipe 36 is held in the coupling 34 by the bushing 35 engaging the flange 37 through an interposed packing ring 38. By this means the pipe 32 and the coupling 34, with the parts carried thereby, may be rotated on a longitudinal axis without disturbing the pipe 36, and at the same time air under pressure from the train pipe is prevented from escaping at the joint by the packing ring 38.

Fast on the pipe 32 is a collar 39 from which radiates an arm 40, and connected to the end of this arm 40 is a link 41 which in turn may be connected to suitable other connections within reach of the engineman in the 95 cab of the engine. It is not deemed necessary to illustrate the connections of the link 41 to the engine cab, as these connections may be of any desired type.

On the pipe 32 remote from the coupling 34 and beyond the corresponding bracket 33 is secured a valve member 42 having a hollow body portion of frusto-conical shape, and through one side wall of this body portion is a port 43. The valve member 42 has formed on it at the pipe end an exterior circumferential flange 44, which flange, however, is cut away for about one-half of its circumference. Exterior to the valve member 42 is another valve member 45 having a frusto-conical or tapering inner surface closely fitting the outer surface of the valve member 42. The valve member 45 is provided with a longitudinally-extending lug 46 entering the space in the cutaway portion of the flange 44 on the member 42. The lug 46 is of less circumferential length than the cutaway portion of the flange 44 so that the member 45 may have a limited circumferential movement upon the member 42. The valve member 42 beyond the member 45 is formed with a neck threaded on the exterior for the reception of nuts 47, one of which serves to confine the valve member 45 on the valve member 42 and the other of which acts as a lock nut for the first nut. Beyond the threaded neck is a continuation thereof shown at 48 and plain on the exterior, so as to be journaled in a bracket 49 mounted on the engine frame 24. The interior of the portion 48 is 130

threaded for the reception of a plug 50. The neck end of the valve member 42 is normally closed by the plug 50, which should make an air tight connection at this point. Under 5 some circumstances it may be desirable to connect another pipe to the neck extension 48, in which case the plug 50 is omitted, and the pipe is screwed directly into the said neck 48.

10 The valve member 45 is provided with a port 51, which may be moved into and out of coincidence with the port 43 and the valve member 42, and this port 51 communicates with the external atmosphere.

15 Projecting radially from the valve member 45 is an arm 52, and this arm is in the path of the upper end 53 of a rod 54 connected at its lower end by a pivot pin 55 to the side walls of the channel iron constituting the shoe 29.

20 The upper end of the rod 54 is guided by a plate 56 fast on the frame 24 and extending under the valve made up of the members 42 and 45, and this plate is turned up over the valve to project into the path of the arm 52 25 thereby limiting the movement of this arm in an upward direction, the downward movement of the said arm being limited by the upper end of the rod 54.

The rod 22 fast to the bell-crank lever 18 30 is continued away from the track to a semaphore post and is there connected to a bell-crank lever 56 which in turn is connected by a link 57 to a semaphore arm 58, and the bell-crank 56 is in turn connected by a rod or link 35 59 to a suitable point of manipulation by an operator stationed at the corresponding block station.

It will be assumed that the system is applied to a single track system such as shown 40 in Fig. 1, then there will be two semaphore arms 58 upon each semaphore post at a block station, and there will also be two track members under the control of the operator at the particular block station. Let it be assumed that at some particular block station 45 the semaphore arm or target 58 is set in the danger position. Under these conditions the rod 22 is moved in the direction toward the track member, and under the action of the springs 12 the movable parts 7 are raised 50 to the position shown in Fig. 2. The highest portion of the spring-controlled parts 7 are in the path of the shoe 29 on the engine. Should an engineman fail to observe or obey 55 the block against him, then as soon as the engine arrives at one of the track members the shoe will engage the inclined surface of the part 7 and ride thereupon and be elevated by the said inclined surface. The springs 12 are 60 sufficiently strong to cause the elevation of the free end of the shoe 29, but at the same time may yield a little to prevent too hard impact, thus providing a certain yielding or elasticity which will tend to prevent damage 65 to the structures. When the shoe 29 is ele-

vated the upper end of the rod 54, which is normally in contact with the arm 52, causes the latter to be moved upward, and the valve member 45 is correspondingly rotated upon its longitudinal axis until stopped by the 70 overhang 57. This movement of the valve member 45 will bring the ports 43 and 51 in coincidence, and the train pipe is thereby put into communication with the external atmosphere. This will reduce the train pipe pressure 75 and the brakes will be applied in the usual manner, the application of the brakes being either the emergency or the full service application, depending upon the size of the ports 43 and 51. This will occur whenever 80 a train passes a block station with the target held against it, no matter what may be the cause of the train passing such station, and this stopping of the train is entirely outside the volition of the engineman. 85

Should it transpire that the target is set at safety, then the rod 22 is moved away from the track member and the bell-crank lever 18 is moved on its pivot from the position shown in Fig. 4 to a position drawing the link 14 90 downward and thereby moving the parts 7 also downward against the action of the springs 12 and out of the path of the shoe 29, so that an engine may pass the track member without the brakes being applied. 95 There is shown the position of the members 42 and 45 of the valve controlling the train pipe when the valve is in its normal position, that is with the ports 43 and 51 out of coincidence and the arm 52 in operative relation to 100 the rod 54. In Fig. 8 the position of the two members of the valve is shown when the latter has been operated by the movement of the rod 54 under the action of the shoe 29 when actuated by the track member. If, 105 now, the train has been stopped and it is desirable that the brake be released, then the engineman, through a suitable manipulation of the rod 41, is enabled to turn the pipe 32 on its longitudinal axis, and so by the engagement of the flange 44 with the lug 46 on the valve member 45, restore the latter to the position shown in Fig. 9. The ports 43 and 51 are however still in coincidence and the brakes are still applied. Now, by reversing 110 115 the movement of the pipe 32, the valve member 42 is again restored to the position shown in Fig. 7 and the ports 43 and 51 are again out of coincidence.

In the structure shown in Fig. 2 it is assumed that the train is moving toward the left and that the target has been set against the engineman and that he has ignored the target. The shoe 29 is assumed to have passed the apex of the track member and the valve in the train pipe has been operated to an extent to open the train pipe to the external atmosphere, and thus set the brakes. 125

The eye 15 in the link 14 permits the downward movement of the link with the 130

part 7 connected thereto, under the impact of the shoe 29 without putting strain upon the bell-crank lever 18 or the rod 22.

This invention has been described as adapted for a block system. It is to be understood that it is equally adapted for a train order system, and in practice it is so used, therefore, the term "block system" or "block signal" is to be understood as comprehending a train order system or block system indifferently.

The link 41 is, in practice, usually operated by the foot of the engine man, but in some engines it may be necessary to otherwise cause the operation of the valve controlled by said link and so the invention is not to be understood as limited to the use of the operating means indicated by the link 41.

What is claimed is:—

1. In a railway block signal, a track member comprising a main section, two vertically yielding sections hinged together at their normally highest point, and a sliding connection with the base section at their ends, and springs housed in the track member between the base and the yielding sections.

2. In a railway block signal, a track member comprising a base section having spaced sides, two vertically-yielding sections having sides straddling the spaced sides of the base section, the said yielding sections being hinged together at their normally highest points and in sliding connection with the base section at their ends, and springs housed in the track member between the base and yielding sections in the space between the sides thereof.

3. In a railway block system, a track member comprising a base section with spaced sides wide at the middle and sloping toward the ends, two yielding sections joined at contiguous ends and having sliding connection with the base section at the ends of the latter, the said yielding sections having sides widest at the junction of the said sections and tapering toward the ends, and springs between the base section and the yielding sections and housed between the sides thereof.

4. In a railway signal system, a track member comprising a base section with spaced sides tapering from the center toward the ends, the base section having the ends returned upon themselves in spaced relation to said base section to form guideways or pockets, top sections having sides straddling the sides of the base section, the said top sections being joined together midway of the length of the base section and the sides of the top sections tapering toward the ends of the base section and the ends of the top sections entering the guideways or pockets formed in the ends of the base section, and springs housed between the sides of the base section and engaging the top sections.

5. In a railway block signal, a track member comprising a base section with spaced sides tapering from the center toward the ends, the base section having the ends returned upon themselves in spaced relation to said base section to form guideways or pockets, top sections having sides straddling the sides of the base section, the said top sections being joined together midway of the length of the base section and the sides of the top sections tapering toward the ends of the base section and the ends of the top sections entering the guides or pockets at the ends of the base section, springs supported and housed in the base section and engaging the top sections, and manipulating means connected to the joined ends of the top sections.

6. In a railway block signal, a track member having two vertically yielding sections connected at their contiguous ends and capable of sliding movement at their remote ends, and manipulating means connected to the joined ends of the yielding sections.

7. In a railway block signal, a track member having two vertically yielding sections connected at their contiguous ends and capable of sliding movement at their remote ends, manipulating means connected to the joined ends of the yielding sections, and a semaphore or signal included in and actuated by said manipulating means.

8. In a railway block signal, a vertically yielding track member, and manipulating means therefor including a bell-crank lever below the middle portion of the yielding member, and a coupling between the bell-crank lever and said yielding member consisting of a link connected at one end to the middle portion of the yielding member and at the other end having a long eye connection to the bell crank lever.

9. In a railway block signal, a vertically yielding track member, a bell-crank lever below the middle portion of the yielding member, a coupling between the bell-crank lever and said yielding member consisting of a link connected at one end to the middle portion of the yielding member and at the other end having a long eye connection to the bell-crank lever, connections from the bell-crank lever to a point of manipulation, and a semaphore or signal means connected to and actuated by said last-named connections.

10. In a railway block signal, a track member, a train-carried member comprising a shoe pivotally supported at one end and yieldingly supported at the other end, and means carried by the shoe for operating train-controlling devices.

11. In a railway block signal, a track member, a train carried member comprising a shoe pivotally supported at one end and yieldingly supported at the other end, a sliding rod carried by the shoe, a valve in the

- path of but unconnected with said rod, and means other than the rod for moving the valve to initial position after being actuated in one direction by the rod.
- 5 12. In a railway block signal, a track member, a train-carried member comprising a shoe formed of a curved strip of channel iron pivotally supported at one end, and a chain support for the other end of the shoe, a sliding rod carried by the shoe, and a valve in the path of said rod.
- 10 13. In a railway block signal, a track member, a train-carried member, and means controlled by the train-carried member, for operating the brake system of the train, comprising a valve movable by the train-carried member, and an air pipe coupling the valve to the air system of the air brake, said pipe being movable about its longitudinal axis and also controlling the valve.
- 15 14. In a railway block signal, a track member, a train-carried member, and means controlled by the train-carried member for operating the brake system of the train, comprising a valve movable by the train-carried member, an air pipe coupling the valve to the air system of the air brake, said pipe being movable about its longitudinal axis and also controlling the valve, and means controllable from a distance to actuate the air pipe.
- 20 15. In a railway block signal, a track member, a train-carried member, and means controlled by the train-carried member for operating the brake system of the train comprising a valve movable by the train-carried member, an air pipe between the valve and the air system of the air brake, and a swivel coupling between the air pipe and the train pipe of the air brake system, whereby said air pipe may be moved about its longitudinal axis and so control the valve.
- 25 16. In a railway block signal, a track member, a train-carried member, and a valve on the train controlling the air brake system and itself controlled by the train carried member, said valve comprising two ported members both movable on a longitudinal axis and one movable relatively to the other.
- 30 17. In a railway block signal, a track member, a train-carried member, and a valve on the train controlling the air brake system and itself controlled by the train-carried member, said valve comprising two ported members both movable on a longitudinal axis, one valve member being movable by the train-carried member, and means other than the train-carried member for moving the other valve member.
- 35 18. In a railway block signal, a track member, a train-carried member, and a valve on the train controlling the air brake system and itself controlled by the train-carried member, said valve comprising two concentric ported members both movable on a longitudinal axis, one valve member being movable by the train-carried member, and means other than the train-carried member for moving the other valve member to restore the air brake system to normal working conditions.
- 40 19. In a railway block signal, a track member, a train-carried member, a valve on the train controlling the air brake system and itself controlled by the train-carried member, said valve comprising two concentric ported members, one movable on its longitudinal axis by the train-carried member to bring its port into coincidence with the port in the other member and so open the air brake system to the atmosphere, and means controllable on the train for moving the other valve member on its longitudinal axis to restore the first valve member to normal position and so close the air brake system to the atmosphere.
- 45 20. In a railway block signal, a track member, a train-carried member, a valve in the train pipe of the air brake system on the train, said valve comprising two ported members, one member being under the control of the train-carried member, a pipe connected to the other valve member, a swivel connection between the said pipe and the train pipe of the brake system, and means for rotating the first-named pipe together with the valve member carried thereby on its longitudinal axis.
- 50 21. In a railway block signal, a track member, a train-carried member, and a valve in the train pipe of the air brake system on the train, said valve comprising two concentric ported members, one valve member being under the control of the train-carried member when actuated by the track member, and the other valve member being controllable from the train, each of said valve members being independently rotatable on its longitudinal axis for a limited distance, one valve member having an incomplete annular flange and the other valve member having a lug entering between the ends of the incomplete flange on the first-named valve member to cause the two valve members to move together after completing their independent movement.
- 55 22. In testimony that we claim the foregoing as our own, we have hereto affixed our signatures in the presence of two witnesses.
